(57) **CLAIM**

The ornamental design for a light having a bendable neck, substantially as shown and described.

DESCRIPTION

FIG. 1 is a perspective view of an ornamental design for a light having a bendable neck, with the bendable neck thereof formed to a first shape;

FIG. 2 is a perspective view of the light having a bendable neck, with the bendable neck thereof formed to a different shape;

FIG. 3 is a side view of the light having a bendable neck, with the bendable neck thereof formed to a different shape, wherein the opposite side is a mirror image;

FIG. 4 is a side view of the light having a bendable neck, with the bendable neck thereof formed to a different shape, wherein the opposite side is a mirror image;

FIG. 5 is an end view of a first end thereof; with the bendable neck thereof in a shape similar to FIG. 2, shown broken away for ease of illustration;

FIG. 6 is an end view opposite the end view in FIG. 5;

FIG. 7 is a side view of the light having a bendable neck as in FIG. 4, but having certain features not part of the design shown in broken line; and,

FIG. 8 is a side view of another side of the light having a bendable neck as in FIG. 7, but having certain features not part of the design shown in broken line.

Broken lines in the illustrations of the DRAWING indicate unclaimed parts of the article or unclaimed environment, or both, that are not part of the design illustrated herein.
